DEMOUNTABLE SUPPORT FOR GARMENTS
AND THE LIKEEdna Smith Eakin and Willard D. Eakin,
Akron, Ohio

Application June 17, 1944, Serial No. 540,762

2 Claims. (Cl. 211—177)

1

This invention relates to demountable supports for garments and the like.

Its chief objects are to provide a device of this character adapted for quick and easy assembly and disassembly; to provide a device which in its disassembled condition will require but little space for storage or for shipment; to provide a device having good strength and stability when assembled; and to provide simplicity of construction and economy of manufacture.

A more specific object is to provide a take-apart rack for coats and hats such as to be suitable for intermittent use in homes, so that it will be unnecessary to employ the common expedient of stacking the guests' coats and hats on beds, with its objectionable results such as crumpling of the bed and the articles stacked upon it and the transfer of lint from the bed-spread to the clothing.

A further object is to provide an assembly consisting of few and simple parts but adapted for various uses.

Of the accompanying drawings:

Fig. 1 is an elevation, with parts sectioned and with parts broken away, of a coat and hat rack embodying our invention in its preferred form.

Fig. 2 is a section on line 2—2 of Fig. 1.

Fig. 3 is an elevation of one of a pair of foot members such as are employed in the assembly shown in Fig. 1.

Fig. 3a is an elevation of the other foot member of said pair.

Fig. 4 is a section on line 4—4 of Fig. 1.

Fig. 5 is a fragmentary elevation, with a part sectioned and broken away, of a member that is shown in Fig. 1 and additional parts associated with it, illustrating an alternative manner of use.

Referring to the drawings, the assembly shown in Figs. 1 to 4 comprises a pair of simple standards 10, 10 preferably pipes for lightness, each of which is formed with four slots 11, 11 (Fig. 4) which are of equal length and are equally spaced circumferentially of the pipe and extend lengthwise of the pipe from its lower end face.

Similar slots 12, 12 can be formed in the upper ends of the pipes 10 for use of the pipes individually as illustrated in Fig. 5, but the slots 12 have no functional importance when the pipes are used in the assembly shown in Fig. 1.

The slots 11 of each pipe 10 (Fig. 4) are adapted to receive a pair of foot members 13, 14. The foot members preferably are of stamped sheet-metal, or of other sheet material. As shown in Fig. 3 the member 13 is formed at its middle with a slot 15 extending upward from its lower edge

2

and the member 14 is formed at its middle with a slot 16 extending downward from its upper edge, each slot being of such width as to receive the sheet material of the other foot member with preferably a fairly snug fit, although this is not essential, and the two feet members, by reason of the slots 15, 16, are adapted to be mated, in the slots 11 of the post 10, with their upper edges flush with each other and with their lower edges flush with each other, their relationship then being as shown in Fig. 1.

The weight of the pipe 10 is sufficient provision for keeping the pipe and its two foot members in assembled relation while they are in use, but to assure that the feet will be lifted when the pipe is lifted, and to protect the fingers of pipe metal, between the slots 11, from excessive prying strain, the lower ends of those fingers can be joined with each other, as by threading the lower end of the pipe, preferably before the slots 11 are cut, making the slots 11 of such length that the finger portions of the pipe will extend below the lower edges of the foot members 13, 14, and applying a washer 17 and a nut 18 to the threaded portion of the pipe.

The construction as described is such that the pipe-margins which define the slots 11 have a bearing against each of the foot members 13, 14 all of the way from the upper margins to the lower margins of the latter, so that a strong joint is provided.

Each assembly consisting of one of the pipes 10 and its foot structure is adapted to stand alone with good stability, which can be increased, if desired, by making the foot members 13, 14 of heavier metal than the aluminum alloy which preferably is used for the pipes 10 and other parts, or by otherwise weighting the base structure.

40 The assembly shown in Fig. 1 comprises also a bridge structure here shown at a hat tray 19, preferably formed of sheet-metal and having an upturned marginal flange 20 (Fig. 2) at each of its length-wise margins. The tray member 19 can be reinforced if desired by a sheet-metal strip 21 secured to its under surface as by rivets 22, 22 and having downwardly bent marginal flanges 23, 23 for strength.

Secured to each end of the tray member 19, as by the riveting shown at 24, is a downwardly projecting pin 25 adapted to be received, preferably with an easy sliding fit, in the upper end of the adjacent pipe 10.

Secured to the under side of the tray 19, as by 55 the riveting shown at 26, 26, is a horizontal rod

or pipe 27 adapted to receive and support coat hangers such as the one shown at 28.

Even though the foot members 13, 14 be left assembled with the posts, the assembly, when taken apart, can be stored with the use of but very little floor space, as by standing the tray sub-assembly and the two post sub-assemblies in a closet, and as there are only three of the sub-assemblies the device can be easily and quickly taken apart and stowed away or brought out and set up for use.

While the tray 19 is shown as reinforced by the sheet-metal strip 21, it is desirable that it have, nevertheless, slight torsional flexibility, so that each foot assembly 13, 14 can find its own firm bearing upon the floor of the room in spite of unevenness of the floor or other imperfection of dimensions, and for the same reason, as well as to provide easy assembly and disassembly, it is desirable that there be a little looseness of the fit of the pins 25 in the pipes 10.

The load-receiving portion of the bar 27 being substantially rigid with the tray and being lower than the points of support of the tray, at the tops of the posts 10, the hanging of coats on the bar increases the stability of the tray and of the assembly as a whole.

For storage in still smaller space, or for shipping, the foot members can be easily removed and laid together flat-wise.

As illustrated in Fig. 5, each one of the post assemblies can be used as a single-standard hat and coat rack by mounting in its slots 12 at its upper end a pair of sheet-metal stampings 29, 30 formed and assembled in a manner similar to that above described with respect to the foot members 13, 14, the stampings 29, 30 being held in the slots 12 by gravity and yet having good stability against the weight of coats and hats hung upon them by reason of the fact that the margins which define the slots 12 have vertically wide bearing against the stampings.

Numerous modifications are possible without departure from the scope of the invention as defined by the appended claims.

We claim:

1. A support for garments and the like comprising a pair of standards each having a foot structure of which floor-engaging areas are widely distant in at least three directions from

the vertical line of the standard's center of gravity, so that the standard has stability in standing alone, and a bridge structure having thereon means telescoping with and seating upon the upper ends of the standards by simple, vertical movement, for removably holding the bridge structure thereon, the bridge structure comprising, as a single handling unit, hat-supporting means and garment-suspending means, and the bridge structure, having simple, telescopic relation to the standards, constituting the only essential connection between them, the connection of the standards by the bridge structure being sufficiently non-rigid to permit each of the standards to maintain its position of independent stability when the assembly is mounted upon an appreciably uneven floor.

2. A support as defined in claim 1 in which the garment-suspending means has its load-engaging portion at least approximately in the middle vertical plane of the telescoping means and below the bridge structure's points of support on the standards, with sufficient rigidity of the bridge structure from said load-engaging portion to said telescoping means to provide substantial leverage for weight of the garments to stabilize the bridge structure.
